ABSTRACT OF THE DISCLOSURE

A metal tensioning strip is wrapped around a cathode ray tube at the faceplate seam to prevent implosion. One end of the strip is secured to a mounting angle which is permanently positioned between the tube and the overlapping layers of the strip as it is wrapped around. The overlapping portions are welded together to maintain the tension.

BACKGROUND OF THE INVENTION**Field of the invention**

The invention relates to a method to apply a tensioning strip which surrounds a cathode ray tube in the zone of the seam between the cone-shaped body and the faceplate portion, under a mechanical bias.

Description of the prior art

The prior art already describes cathode ray tubes around which are wound in the zone between the faceplate and the conical portion of the tube ribbons of plastic or artificial resin or other similar material such as hemp, cord, or other textile fabric or braided ribbon of fibre glass, nylon, perlone or jute which are applied with the aid of a binding agent. In these arrangements the protection against implosion is substantially achieved by the binding agent which partly penetrates into the ribbon and forms, after hardening, a uniform envelope.

It is also known to use a shielding cap of ferromagnetic material surrounding the conical portion of a cathode ray tube said cap consisting of a metal ribbon wound in a suitable shape. Such a magnetic shielding cap however is unsuitable to avoid implosions of cathode ray tubes. From U.S. Pat. Nos. 2,785,820; 2,874,017; 3,220,592 and 3,220,593 cathode ray tubes are known which are surrounded against implosion with a ribbon or strip being mechanically biased and consisting of highly elastic material, applied onto the cathode ray tubes at the critical zone. The mechanical biasing of the ribbon is made in most of the arrangements in that said ribbon or parts thereof are led around the cathode ray tube and mechanically tensioned or biased, when connecting the free ends of the ribbon or of the parts thereof with the aid of screws or of a turnbuckle.

Such a tensioning method shows the big disadvantage that the individual parts of the ribbon or strip or of parts thereof are extended differently during tensioning which is extremely unfavorable for safety of the tubes against implosion. The only method known, in order to apply a tensioning ribbon which was uniformly expanded prior to its application to the tube or the entire circumference, consists, according to said patent specifications in that the ribbon is uniformly heated prior to its application onto the tube and is shrunk onto said tube during cooling. But this method has so many disadvantages that it was never applied in practice. The heated tensioning ribbon may easily cause damages of the tube; moreover, it is required, due to variations in the diameter of the tube, to use for each circumference a tensioning ribbon of a defined size, because such variations in circumference

2

cannot be compensated by the heating temperature applied to the tensioning ribbon, as the heating of the tensioning ribbon is possible only within a defined temperature range in order to avoid cracks in the glass due to a sudden heating. Finally the temperature increase causes changes of the surface structure and of the appearance of the tensioning ribbon.

Another method in which a metallic tensioning ribbon is applied onto the critical zone of a cathode ray tube under a uniform pulling stress, is described in the French patent specification 1,406,501. In this method one end of the ribbon is secured with the aid of a holding device, whereupon the ribbon is wound round the tube under a defined pulling force and thereupon welded together. After welding, the welding electrodes and fixing claws of the holding device, arranged between the wall of the tube and the ribbon are removed. Thereby the tension of the ribbon is reduced. To obtain a predetermined final tension of the ribbon it is therefore required to consider when tensioning the ribbon, the loss caused by removing of the fixing claws and of the welding electrodes between tube and ribbon. It is therefore necessary to tension the ribbon more when applying it than it is stressed or tensioned in its final condition.

SUMMARY OF THE INVENTION

It is the object of the present invention to provide a method in which the tensioning ribbon possesses in its final position substantially the tension with which it was applied onto the tube. Another object of the invention is to fix, together with the applying of the tensioning ribbon, the angles with the aid of which the cathode ray tube is mounted inside the equipment.

In a method to wind a metallic tensioning ribbon onto the critical zone of a cathode ray tube under the application of a uniform pulling force and the following welding of the tensioning ribbon one end of the tensioning ribbon is fixed, according to the present invention, at the limb of the mounting angles of the tube within the housing, being parallel to the sidewall of the tube and thereupon the tensioning ribbon is wound over the parallel limbs of the mounting angles and kept in place by means of a holding device, and thereupon the overlapping parts of the tensioning ribbon are welded together.

Although a tensioning ribbon consisting only of one winding, results in a safe protection against implosion it may be of advantage for production reasons, that the tensioning strip or ribbon consists of several windings one above the other. Such a tensioning ribbon may consist of an essentially thinner material for the individual windings. This has the advantage that the windings of thinner material fit the surface of the critical zone still better than a single winding of thicker material. It is of particular advantage to use the limb of one of the fixing angles of the tube, being approximately perpendicular to the wall of said tube as the current lead for the welding process.

The inventive method shows the advantage that between the wall of the tube and the ribbon to be wound around said tube neither temporary removable fixing devices nor welding electrodes must be provided. It is thereby achieved that the tensioning ribbon must be mechanically biased during its winding around the tube only to such an extent as it should be in the final condition. Moreover the limb of the fixing angle being approximately perpendicular to the wall of the tube offers a particularly favorable connection for one of the electrodes for the welding of the tensioning ribbon. The other welding electrode is then placed on the appertaining portion of the tensioning ribbon, located on the limb in parallel to the tube's wall.

BRIEF DESCRIPTION OF THE DRAWINGS

The invention is now explained in detail with the aid of an example shown on the accompanying drawings.

FIG. 1 is a cross section of the cathode ray tube showing the overlapping tensioning ribbon and mounting or fixing angles, and

FIG. 2 shows the method of wrapping the ribbon around the tube.

DESCRIPTION OF THE PREFERRED EMBODIMENT

The cathode ray tube 1 is mounted in the device 2 and 2a. This mounting device may rotate around the longitudinal axis in the direction of the arrow. Part 2 of the device is provided with a vacuum pump, the vacuum connection or outlet designated by 8. The device 2a also accommodates fixing angles 3 which keep the tube in place after installation in the equipment. In the example shown the metallic ribbon 4 is secured on the angle 3 at the left side by welding or riveting. The ribbon 4 is reeled off from the ribbon reel 5. In order to guarantee a uniform pulling force the reel is braked by the brake 6 and the weight 7. By changing said weight 7 the pulling force exerted on the ribbon during the winding can be changed. Instead of braking the reel 5 it is also possible to have a weight directly effect the ribbon via a roller. The ribbon is wound around the tube in such a way that the fixing device 2, 2a rotates together with the cathode ray tube 1 around the axis in direction of the arrow so that ribbon 4 is reeled off the reel 5 and wound around the circumference of the tube and around the limbs of the fixing angles, parallel to the tube wall. This winding process can be made in such a way that the tube is surrounded by one winding only; but also several layers of windings may be provided. In such a case it is possible to use a substantially thinner metal band and consequently also less pulling force. After the desired number of windings has been applied onto the critical zone of the picture tube the ribbon is welded together in such a way that one of the

welding electrodes is connected to the radially outward directed limb of the fixing angle to which the ribbon has been welded, while the other welding electrode is placed on the ribbon. After welding, the ribbon is cut. By this cutting the pulling force exerted on the ribbon 4 and maintained during the welding process, is cancelled. Instead of having the tube rotating when applying the ribbon 4 it is also possible to keep the tube steadily in place and to lead the ribbon reel 5 around the tube, applying the desired uniform pulling force, until the desired number of winding layers are on said tube.

While only a single embodiment has been illustrated, other variations may be made in the method and configuration without departing from the scope of the invention as set forth in the appended claims.

What is claimed is:

1. A cathode ray tube protection device comprising a tube having a conical portion and a faceplate with a seam therebetween, mounting means disposed on the surface of said tube at said seam, a metallic tensioning ribbon wrapped around the periphery of said tube over said seam, one end of the ribbon being secured to said mounting means, a portion of said ribbon overlapping said one end and an underlying layer and being welded to said layer to maintain the tension with the mounting means remaining in position.

2. The device of claim 1 wherein said ribbon includes a plurality of overlapping layers.

3. The device of claim 1 wherein said mounting means comprises an angle having a limb on said surface and said one end is welded to said limb.
